Atty's.

UNITED STATES PATENT OFFICE.

WILLIAM BERTRAM BOLLES, OF MILWAUKEE, WISCONSIN.

EMERGENCY-DOOR-LOCK-OPERATING MECHANISM.

1,383,973.

Specification of Letters Patent.

Patented July 5, 1921.

Application filed September 30, 1918. Serial No. 256,234.

To all whom it may concern:

- Be it known that I, WILLIAM B. BOLLES, a citizen of the United States, residing at Milwaukee, in the county of Milwaukee and 5 State of Wisconsin, have invented a certain new and useful Improvement in Emergency-Door-Lock-Operating Mechanism, of which the following is a full, clear, and exact description.
- 10 This invention relates to a device for use in connection with doors, more particularly exit doors from theaters, halls, and other buildings.
- 15 The purpose of the invention is to provide a means whereby the lock or locking means for a door may be easily operated by a bar, handle, lever, or similar element which is so placed upon the door as to be readily accessible to persons seeking exit.
- 20 A further purpose and object is to provide such a mechanism, which is simple in construction, and one in which the parts are so arranged and guided that the parts can not jam, and thereby be non-effective in the 25 process of opening the door.

Generally speaking, the invention may be said to comprise the elements and combinations thereof set forth in the accompanying claims.

30 Reference should be had to the accompanying drawings forming a part of this specification, in which Figure 1 is an elevation showing a door equipped with locking bolts and operating mechanism for the 35 same; Fig. 2 is an elevation of the mechanism by which the bolts are operated; Fig. 3 is a side elevation with portions in section of the construction such as shown in Fig. 2; Fig. 4 is an elevation showing a 40 modified form of construction; Fig. 5 is an elevation showing a modified form of construction; and Fig. 6 is an elevation showing a modified form of construction.

45 Referring to the drawings, 1 indicates a door, 2 and 3 indicate locking bolts for the door which coöperate with suitable detention devices carried in the door frame and by the floor adjacent the bottom of the door.

Either formed as part of these latches, or 50 secured thereto, are rods 4 and 5. These rods are secured to sliding members 6 and 7, such as indicated in Fig. 2. The sliding members are in part mounted within the casing 8, this casing having a cover such as 55 indicated at 9 in Fig. 3, which normally occupies the position shown in that figure,

The casing 8 with its contents is secured to the door after the fashion indicated in Fig. 1.

Within the casing I extend the sliding 60 members 6 and 7, as indicated, and coöperating with the sliding member 6 is a wall 10 which preferably is formed integral with the casing, also a short wall 11, which co- 65 operates with an opposite side of the sliding member. The member 6 also bears against the face of the casing 8 and is engaged by the cover 9 when it is facing any position. Thus the member 6 is held against movement, and the fit between the various parts 70 which engage the member 6 is such as to permit a free movement of the member 6, but nevertheless to prevent any movement in a direction otherwise than substantially linear.

75 The member 7 also engages in part with the wall 10, and preferably there is a wall 12 which also engages with the member 7 to assist in guiding it in a linear direction. Adjacent the lower end of the casing there 80 is a wall 13, also a short wall 14, which engage with the sides of the member 7 for the purpose of guiding the same.

The member 7 is provided with an extension 7^a and the member 6 is provided with 85 a recess or socket portion 6^a. The recess 6^a receives a coil spring 15, and the head 7^a of the member 7 extends within the recess 6^a and engages with the end of the coil spring 15, so that when the members 6 and 7 90 move toward each other, the coil spring is placed under compression, which compression serves to restore the members 6 and 7 to their normal position when the pressure which holds spring 15 compressed, is released.

95 The members 6 and 7 are adapted to be moved simultaneously so that the latches for the door at the top and bottom thereof will be simultaneously moved, that the door may 100 be opened.

For the purpose of so joining the members 6 and 7 that they may be simultaneously moved, I employ a pivoted lever 16, which lever is pivoted at its central portion, and 105 at each of its ends is provided with an up-standing pin, as indicated at 17 and 18. The member 6 has an extension 6^b which is provided with a pin 6^c. This extension is preferably provided with a part 6^d which engages with a wall of the casing 8, so that as the member 6 and the parts 6^b and 6^d are

moved, the bearing of the portion 6^a upon the casing will serve to take a part of any thrust, and assist in enabling the members 6 and 7 to move in a linear direction.

5 Link 19 co-operates with the pins 17 and 6^c. The member 7 is provided with an extension 7^b which has a part 7^c that engages with the wall of the casing 8. This portion 7^c serves when the members 6 and 7 are moved, together with the walls 10, 12, 13, and 14, to maintain the same in proper linear arrangement. The extension 7^b is provided with a pin 7^d. A link 20 co-operates with the pins 7^d and 18.

15 As before stated, the lever 16 is pivoted at its central portion, as indicated at 16^a, and the lever 16 extends beneath the member 7, and for this purpose, the member 7 is mortised clear through, as indicated in dotted lines at 7^e in Fig. 6.

Upon the casing there is pivoted a lever 21. This lever is provided with a rearwardly extending portion 21^a as indicated in Fig. 3. Above the lever there is a portion of the casing indicated at 22, which in part extends over that portion of the lever 21 at which it is pivoted, so as to prevent the hand or clothing of the operator from becoming caught behind the lever and preventing the 30 operation thereof.

The extension 21^a of the lever 21 may be described as substantially cylindrical in its shape except at that portion by which it is joined to the lever 21. The extension 21^a of the lever extends into and occupies an opening 7^f which is formed in the member 7, the member 21^a normally engaging with the top portion of the said opening. The mechanism which has thus far been described will 40 operate when the lever 21 is depressed, and by its operation will cause the members 6 and 7 to simultaneously move into the casing, or toward each other and compress the spring 15. This will at once be evident by 45 an examination of the drawings, for when the lever 21 is depressed, it will cause the sliding member 7 to move inwardly with respect to the casing. This movement will cause the link 20 to raise the pin 18, which 50 will in turn depress the pin 17, and this will in turn cause the link 19 to act upon the pin 6^c, thereby causing the member 6 to move into the casing. Therefore, by the operation of the lever 21, the sliding members 6 and 55 7 are simultaneously operated.

As soon as the lever 21 is released, the spring 15 tends to assume its normal position and move the members 6 and 7 to their original and normal position.

60 It may happen that the person endeavoring to operate the lever 21, would, in the excitement of a hasty egress, grasp the lever 21 and raise it instead of pushing it down, and in order to provide for such a contingency and make it possible to release the

locking bolts under such a situation, I have provided the following construction.

The member 7 is provided with a recess 7^g mortised out. A link 23, co-operates with the pin 17, and at its lower end has an extension 23^a which extends into the recess 7^g and normally lies just beneath the portion 21^a of the lever 21. This link 23 is preferably provided with a roller 24, adjacent its lower end, which engages with the side wall 75 of the casing 8 in order to provide a rolling contact between the roller 24 and the wall of the casing 8, and further to provide a backing for the lower end of the link 23.

The recess 7^g is sufficiently extended so 80 that the projection 23^a may move through the recess for a sufficient distance to accommodate any movement required for the operation of the members of the mechanism.

The link 23 may be formed integral with 85 the link 19, so that the links 19 and 23 are in effect a single operating member, in which event the opening indicated at 19^a is slightly elliptical in shape to accommodate the 90 slightly circular movement of the pin 17 as the lever 16 tilts about its pivot.

With the members of the mechanism arranged as just described, if the operating lever 21 be raised, the part 21^a of the lever is depressed, which moves the projection 23^a 95 downwardly through the recess 7^g, in turn carrying the link 23 downwardly which communicates its motion to the link 19 and so through to the member 6, causing the same to be moved in a direction into the 100 casing. The downward movement of link 23 causes the lever 16 to tilt, thereby drawing in an upward direction the link 20, which in turn causes the member 7 to move into the 105 casing.

Thus it will be seen that the sliding members 6 and 7 are operated in a manner to withdraw the locking bolts whether the lever 21 be depressed or raised.

In Fig. 6 I have shown a construction in 110 which the members 6 and 7 are the same as that described, and in fact, most of the parts are exactly the same, the only difference being that the link 19 and the link 23 are formed as independent members.

In Fig. 4 I have shown a slightly modified form relating to the manner of connection of the lever 16 with the sliding member 7. In this construction the lever 16 has a pin 16^b which co-operates with an extension 7^j 120 formed on the member 7. This extension is formed adjacent the portion of the member 7 which co-operates with the lever 16, the opening in the portion 7^j being slightly elliptical in form so as to accommodate the slight circular movement of the pin 16^b as it moves. In this form, the links 19 and 23 are formed separately, and are caused each to engage with the pin 17 of the lever 16.

In Fig. 5 the parts are the same as that 130

shown in Fig. 4, with the exception that the links 19^c and 23^c are made integral, and at that portion which coöperates with the lever 16 there is an opening 17^d which is slightly elliptical in form in order to accommodate the pin 17 in its slightly circular movement.

Having described my invention, I claim:

1. The combination with a door and a locking bolt therefor, of a pair of oppositely disposed members mounted to slide upon the door, one of said members being connected with the locking bolt, one of said members being formed with a recess, the other of said members being formed with a projection adapted to slide in said recess, a spring in said recess engaging the said projection, an operating lever pivoted upon the door, and operating connections between the said lever and one of the sliding members.
2. The combination with a door and a locking bolt therefor, of a pair of oppositely disposed sliding members which are in alinement, means engaging the said sliding members for keeping them in alinement as they may slide, one of said members being connected with a locking bolt, one of said members being formed with a recess, the other of said members being formed with a projection which is adapted to slide in said recess, a spring in said recess and engaging the said projection, an operating lever pivoted upon the door, and operative connections between the said lever and one of the sliding members.
3. The combination with a door and a locking bolt therefor, of a pair of oppositely disposed slideable members mounted to slide upon the door, guiding walls engaging portions of the slideable members, one of the members being provided with a recess, the other being provided with a projection which engages with the said recess, a spring which coöperates with said members to normally move them apart, an operating lever pivoted upon the door, and operative connections between the lever and one of the sliding members.
4. The combination with a door and a locking bolt therefor, of a pair of oppositely disposed members mounted to slide upon the door, one of said members being connected with the locking bolt, an operating lever pivoted upon the door and having a portion which is directly connected with one of the sliding members, and link members connecting the said sliding members, one of said link members having a portion which lies in the path of movement of the said portion of the operating lever whereby the sliding members are caused to move the locking bolt to unlocked position when the operating lever is moved in either direction about its pivot.
5. The combination with a door and a locking bolt therefor, of a pair of oppositely disposed members mounted to slide upon the door, one of said members being connected with the locking bolt, an operating lever pivoted upon the door and having a portion which is directly connected with one of the sliding members, a lever pivoted at substantially its central portion, one end of said lever being operatively connected with one of the sliding members, the other end of said lever being operatively connected with the other of said sliding members, a member normally positioned adjacent a portion of the operating lever and adapted to be engaged by the same when the operating lever is moved in one direction about its pivot, said member being operatively connected with the said pivoted lever whereby the sliding members are caused to move to draw the bolts from locking position when the operating lever is moved in either direction about its pivot.
6. The combination with a door and a locking bolt therefor, of a pair of oppositely disposed members mounted to slide upon the door, one of said members being connected with the locking bolt, an operating lever pivoted upon the door and having a portion which is directly connected with one of the sliding members, a lever pivoted at substantially its central portion, one end of said lever being operatively connected with one of the sliding members, the other end of said pivoted lever being operatively connected with the other of the sliding members, a member extending in the path of movement of a portion of the operating lever when the lever moves in one direction about its pivot, a link member operatively connecting said member with the said pivoted lever whereby the sliding members are caused to move to withdraw the locking bolt from locking position when the operating lever is moved in either direction about its pivot.
7. The combination with a door and a locking bolt therefor, of a pair of oppositely disposed members mounted to slide upon the door, one of said members being connected with the locking bolt, an operating lever pivoted upon the door and having a portion which is operatively connected with one of the sliding members, a lever pivoted at substantially its central portion, means for operatively connecting one end of said lever with one of the sliding members, a link connecting the other end of said pivoted lever with the other of said sliding members, a link member operatively connected with the sliding member and having a portion which extends in the path of movement of a part of the operating lever whereby the sliding members are caused to move to withdraw the locking bolt from locking position when the operating lever is moved in either direction about its pivot.

8. The combination with a door and a locking bolt therefor, of a pair of oppositely disposed members mounted to slide upon the door, one of said members being connected with the locking bolt, one of said sliding members being provided with a mortised out part, a lever extending through said mortised out part, said lever being pivoted at substantially its central portion, means 5 connecting one end of said pivoted lever with one of the sliding members, a link connecting the other end of said pivoted lever with the other of the sliding members, a link member operatively connected with the pivoted lever and having a portion which extends in the path of movement of a portion of the operating lever whereby the sliding members are caused to move toward each other to withdraw the locking bolt from 10 locking position when the operating lever is moved in either direction about its pivoted lever.
9. The combination with a door and a locking bolt therefor, of a pair of oppositely disposed members mounted to slide upon the door, one of said members being connected with the locking bolt, a lever pivoted at substantially its central portion, one end of said lever being operatively connected with one 15 of the sliding members, and means operatively connecting the other end of said lever with the other of the said sliding members, one of said sliding members being provided with an opening, and also with a recess adjacent said opening, a member normally occupying said recess and lying adjacent the opening, means connecting said member with the pivoted lever, an operating lever pivoted upon the door and having a portion which 20 co-operates with the recess in the said sliding member and in position to engage with the said member occupying the recess when the operating lever is moved in a given direction about its pivot.
10. The combination with a door and a locking bolt therefor, of a pair of oppositely disposed members mounted to slide upon the door, one of said members being connected with a locking bolt, a lever pivoted at substantially its central portion, means for operatively connecting one end of said lever with one of the sliding members, a link member connecting the other end of said pivoted lever with the other of said sliding members,

one of said sliding members being provided 55 with an opening and also with a recess adjacent the said opening, a link member operatively connected with said pivoted lever, said link having a portion which extends within the recess and adjacent the opening, 60 an operating lever provided upon the door and having a portion which co-operates with the opening in the sliding member and is adjacent that portion of the aforesaid link which extends within the recess whereby 65 when the operating lever is moved in one direction about its pivot it directly engages the sliding member, and when moved in the other direction about its pivot it engages with the projection within the recess. 70

11. The combination with a door and a locking bolt therefor, of a pair of oppositely disposed members mounted to slide upon the door, each of said members being connected with one of the locking bolts, a lever pivoted 75 at substantially its central point, one end of said lever being operatively connected with one of the sliding members, the other end of said pivoted lever being operatively connected with the other of the sliding members, one of said sliding members being provided with an opening, and the other of the sliding members being provided with an extension which engages in said opening, a 80 spring occupying said opening and engaging 85 with the said projection, one of said sliding members being provided with an opening and also with a recess adjacent the opening, a link member operatively connected with said pivoted lever, an extension member 90 associated with said link member and extending into the said recess and adjacent the opening in the sliding member, an operating lever pivoted upon the door and having a portion which co-operates with the opening 95 in one of the sliding members, said lever when moved in one direction about its pivot directly engaging with said sliding member, and said operating lever when moved in the opposite direction about its pivot engaging 100 with the said member which extends within the recess whereby the sliding members are caused to move the locking bolts to unlocked position when the operating lever is moved in either direction about its pivot. 105

In testimony whereof, I hereunto affix my signature.

WILLIAM BERTRAM BOLLES.
